(57) CLAIM

The ornamental design for a display kiosk with marquee, as shown and described.

DESCRIPTION

FIG. 1 is a front perspective view of a display kiosk with marquee, according to my new design;

FIG. 2 is a front side view thereof, the back side view being a mirror image;

FIG. 3 is a left side view thereof, the right side view being a mirror image;

FIG. 4 is a top plan view thereof; and,

FIG. 5 is a bottom view thereof.
